FOLDER FOR BLINDSTITCH SEWING MACHINES

Joseph Galkin, New York, N. Y.

Application November 28, 1949, Serial No. 129,749

2 Claims. (CL. 112—147)

1

This invention relates to improvements in folders for belt loops made on blindstitch sewing machines.

An object of this invention is to provide a folder which will accurately fold a strip of material so that the folded edges thereof are brought together on the upper side of the strip and both edges of the strip concealed inside the belt loop, and a line of blindstitch stitching passed through the folded edges, and partly through the face portion of the belt loop.

Another object of this invention is to provide a folder having two inwardly curved side edges for equally folding both side edges of the strip above the strip and toward each other in abutting relation, and to provide outwardly curved extensions at the outlet end of the folder for folding the fabric strip outwardly into concealment in the belt loop, and to provide means for pivotally mounting the folder to cause the rear portion of the folder to follow the upward movements of the node former of the blindstitch sewing machine.

Another object of this invention is to provide spring means to cause the folder to move downwardly after it is raised by the node former and released.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a top plan view of the folder, pivotally mounted on a work table of a blindstitch sewing machine.

Figure 2 is a side view of the pivotally mounted folder and of a fragmentary portion of the sewing machine shown in Figure 1 and in which the folder is installed.

Figure 3 is a side view of the pivotally mounted folder and folder support.

Figure 4 is a cross-sectional view taken on line 4—4 in Figure 1.

Figure 5 is a front view of the assembled folder and folder support.

Figure 6 is a rear view of the folder and folder support.

Figure 7 is a central cross-sectional view of a modified spring-mounted folder.

Figure 8 is a top plan view of mechanism for feeding a tape into the belt loops.

2

In the illustrated embodiment of the invention, the numeral 10 indicates a folder for belt loops made on a blindstitch sewing machine 11. The machine 11 comprises a work table 12 forming part of a bracket 13 which is secured to the frame 14 of the sewing machine. The bracket comprises a support 15 having a pivot 16 on which the forward end portion of the folder 10 is pivotally mounted to permit upward and downward movement of the rear end of the folder. The support 15 is suitably fixed to the bracket 13 by screws 13'.

A coil spring 17 has one end fixed to a lug 18 at the rear end of the folder 10 and has its other end fixed to a stud 19 threaded in the support 15.

The spring 17 functions as the sole means to bring the outlet end of the folder downwardly in direction of a node former or oscillatory finger 20, well known in the art of blindstitch sewing machines.

Journalized in a forwardly extending horizontal arm 21 of the sewing machine 11 is an oscillatory needle shaft 22. The needle shaft 22 is oscillated from the main shaft of an eccentric on the main shaft which drives a vibratory connection on the needle shaft.

As shown in Figure 2, the shaft 22 extends forwardly beyond the free end of the arm 21. Fixed to the projecting end of the shaft 22 is a needle arm 23 to which a curved needle 24 is attached.

The sewing machine to which the folder 10 is applied is more fully shown in my patent application, Serial No. 100,554, filed June 22, 1949.

The invention is particularly directed to a pivotally mounted folder 10 forming part of a combination of mechanisms operating upon sections or scraps of cloth for fully automatically forming in a single operation blindstitched belt loops, each having edge portions which are concealed internally of the belt loop to prevent ravelling of the edges of the cloth.

The side walls 25, 25 of the folder 10 are inwardly curved. The folder gradually tapers from the receiving end 26 towards the delivery end 27 of the folder, and so that as the strip which is folded leaves the delivery end, the strip is folded equally upwardly upon itself at both sides of the belt loop.

As shown in Figures 1, 4 and 6, it will be seen that the bottom wall of the folder lies flat between the curved side walls 25, 25 and that a clear passage is provided through the folder from the inlet end to the outlet end thereof.

The outlet end 27 of the folder 10 terminates directly in front of the needle 24. As shown in Figures 5 and 6, the side walls 25 have outwardly

curved extensions 29 at the outlet end of the folder. The extensions 29 fold the belt loop fabric outwardly into concealment in the belt loop.

As shown in Figures 4 and 6, the lower face of the rear end portions 27 of the folder 10 has an opening 30 centrally thereof. The opening 30 is of a size permitting the node former 20 to enter directly into the rear end portion 27 of the folder. The downward movement of the folder 10 caused by the spring 17 is arrested by the upper end portion of a slide plate 32 having a slot 33 through which the stud 19 passes into threaded engagement with the support 15.

A threaded nut 34 on the stud 19 permits the slide plate 32 to be adjusted in vertically supported relation. This arrangement permits the adjustment of the folder to be made such that the position of the folded fabric in the folder in relation to the needle 24 causes the needle to only partly penetrate the top surface of the folded belt loop.

As shown in Figures 4 and 5, the base plate 35 of the folder 10 has a central rib 36 having an aperture 37 through which the pivot pin 16 passes. The pin 16 is held in a block 38 which is slidably mounted in a guideway 39 in the folder support 15. A lock screw 40 threaded in the folder support 15 serves for clamping the block 38 in the support 15 so as to bring the delivery end 27 of the folder close to the needle 24.

Figure 7 is a central cross-sectional view of a modified spring-mounted folder 45 comprising a folder support 46 having a block 48 slidably mounted in the support 46, similar to the slideable block 38 shown in Figures 4 and 5.

The block 48 is secured in adjusted relation in the support 46 by a screw 47. A right-angular leaf spring 49 is secured to the block 48 by a screw 50. The folder base plate 51 of the modified folder 45 is secured to the leaf spring 49 by a rivet 52.

The leaf spring 49 is formed so as to urge the folder base plate 51 in a downward direction. A slide plate 53 has a slot 54 through which a bolt 54' passes into threaded engagement with the support 46. The downward movement of the folder base plate 51 is arrested by the upper end of the slide plate 53.

Stationary shear blades 55, 55' are held in properly spaced-apart relation in the folder support 15 by blade clamps 56 and 56' and a clamp screw 57. The screw 57 passes freely through a clearance aperture in the clamp 56 and is threaded in the clamp 56'. Movable shear blades 58, 58' cooperate with the stationary shear blades 55, 55', to cut a fabric strip of predetermined width. The movable shear blades are given downward cutting movements by blade carriers 59, 59' carried by a rock-shaft rotatably and slidably mounted in a bearing 61 in the support 15.

The blindstitch sewing machine 11 is also equipped with a front top feed dog 65 for feeding the fabric between the shear blades and through the folder. The feed arm 66 of the sewing machine 11 actuates the front top feed dog 65.

As shown in Figure 4, the block 38 has an opening 41 of larger size than the diameter of the clamp screw 57. The large opening permits adjustment to be made of the block 38 and of the pivotally mounted folder 10 to bring the rear end of the folder close to the needle.

The carrier 59 is slideable on the shaft 60. The carrier 59' is fixed to the shaft 60. A clamp 69 is fixed to the shaft 60. An elongated key 67 is fixed to the clamp 69 and to the carrier 59'. The key 67 is below and clear of the shaft 60. The carrier 75

59 of the blade 58 is resiliently pressed by a coil spring 68 and causes the blade to press against the stationary blade 55. The spring pressure against the clamp 69 moves the shaft 60 which carries the attached carrier 59' and the blade 58' against the stationary blade 55'. The spring 68 reacts against the clamp 69 and against the carrier 59 and forces both carriers and both movable blades in direction of the stationary blades. A screw 59' secures the carrier 59' to the shaft 60.

Referring to Figure 8, it will be noted that I have provided additional mechanism for feeding a fabric tape 70 into the belt loop. The mechanism comprises a narrow opening 71 in the front portion of the front top feed-dog 65. The opening 71 is positioned centrally of the folder and serves for feeding the tape through the folder. The tape is fed from a spool (not shown) above the base of the sewing machine.

The tape passes below the top feed-dog 65 through the folder and to the needle and is stitched within the belt loop. The tape is concealed inside the belt loop. The tape forms a continuous fabric strip extending from one belt loop to another. The tape serves to stiffen and flatten belt loops made of thin fabric.

I provide a wire spring 72 which is suitably secured at one end to the front top feed-dog 65 and having its free end 73 bent in U-shaped form and resting on the top feed-dog 65. The spring 72 retains the tape 70 in alignment with the opening 71 during the up and down movements of the feed-dog 65.

An extension feed bracket 75 is secured to the sewing machine feed-bar 66 which is given four-motion feeding movements through a mechanism (not shown) but which is well known in the art.

The front top feed-dog 65 is pivotally mounted on a screw 83 passing through the forward portion 84 of the extension feed bracket 75. The front top feed-dog 65 is secured to a carrier 82 which is pivotally mounted on the screw 83. A spring 85 is secured at one end by a screw 86 against the feed bracket 75 and is in tensioned engagement at the other end against the carrier 82. The spring 85 presses the front top feed-dog 65 against the upper surface of the folder base plate 51.

In accordance with the patent statutes I have described and illustrated the preferred embodiment of my invention, but it will be understood that various changes and modifications can be made therein without departing from the spirit of the invention as defined by the appended claims.

I claim:

1. In a blindstitch belt loop sewing machine having a needle and a node former, a folder having two inwardly curved side edges for equally folding both side edges of the belt loop strip above the strip and toward each other in abutting relation, a support therefor, the front end portion of said folder being pivoted on said support to permit said node former to raise the rear end portion of said folder during each stitching operation, the lower face of said folder at the rear end thereof having an opening whereby said node former can enter directly into said folder, said folder having its outlet end portion directly in front of said needle and in far spaced-apart relation from said pivot, said pivot being positioned in alignment with the line of stitching, said folder having two inwardly curved side walls for equally folding both side edges of a belt loop strip above said strip and toward each other, said folder

having an upwardly raised portion centrally thereof and in alignment with said bottom opening, forming a cavity in the belt loop material into which said node former enters to allow said needle to partly penetrate the top surface of the belt loop material.

2. In a blindstitch belt loop sewing machine having a frame, a curved needle, an oscillating node forming means and a bracket; a folder for folding two side edges of a strip of fabric into belt loop form, a support for said folder, the front end of said folder being pivoted on said support to cause the rear end thereof to swing up and down during all the stitching operations, said folder having its outlet end portion directly 15 in front of said needle, said pivot being positioned in alignment with the line of stitching, said folder having two inwardly curved side walls for equally folding both side edges of said strip above said strip and toward each other in abutting relation, said curved side walls having outwardly curved extensions at the outlet end of said folder for folding said fabric outwardly into concealment in said belt loop, said folder having a rearwardly converging passage, said folder having 20 an opening centrally thereof at its lower rear portion, said lower central opening permitting entrance into said folder of means for auto-

matically moving said folder upwardly, the rear end of said folder being movably mounted on said support, a spring having one end secured to said support and the other end secured to said outlet end portion of said folder, causing said folder to be resiliently urged downwardly, an adjusting plate having a slot therein and being slidably mounted at the rear face of said support and contacting the lower rear surface of said folder, and a threaded means threaded in said support and passing through said slot for vertically adjusting said plate for limiting the downward movements of said folder by said spring.

JOSEPH GALKIN.
